TAPE TENSIONING PULLEY FOR SPINNING FRAMES

Gerry Bradley Nutting, Saco, Maine, assignor to Saco-Lowell Shops, Boston, Mass., a corporation of Maine

Application May 2, 1938, Serial No. 205,422

3 Claims. (Cl. 74—240)

As is well understood by those familiar with textile machinery, it is customary to arrange the spindles of spinning and twister frames in two or more parallel rows extending longitudinally of the frame at opposite sides thereof. These spindles are customarily driven from a long cylinder running lengthwise of the frame and located between the rows of spindles, the drive transmitting members consisting of tapes or equivalent elements.

It is highly desirable to maintain substantially the same degree of tension on all the tapes and to hold this tension substantially unchanged by any stretching or shrinking of the tapes. For this purpose each tape is run over a pulley which is acted upon by a weight serving to tension the tape to approximately the desired degree. Usually the pulley is supported on a swinging arm, and the weight acting on that arm to produce the tape tensioning action must also counterbalance the weight of the pulley assembly. For this reason, and also for the purpose of facilitating the maintenance of a uniform tape tensioning action as the pulley swings through its normal arc of movement, it is desirable to make the pulley light in weight.

In addition to this requirement, it is also important to reduce the friction of rotation of the pulley to a minimum, to prevent lint and fly from accumulating on it, particularly where it would increase the friction, and to provide a construction of simple and sturdy design capable of being manufactured economically and of giving long service with a minimum of care or attention.

The present invention is especially concerned with tape tensioning pulleys of this character, and it aims to devise a construction having the desirable qualities above mentioned. While the invention will be herein disclosed as embodied in a pulley designed especially for use in spinning and twister frames, it is contemplated that it may also be used in other textile machines where essentially the same requirements exist.

In the accompanying drawing, which illustrates a preferred embodiment of my invention, Figure 1 is a side view of a tape tensioning pulley and its supporting arm;

Fig. 2 is a vertical, sectional view approximately on the line 2—2, Fig. 1; and

Fig. 3 is a sectional plan view on the line 3—3, Fig. 1.

The construction shown in the drawing comprises a supporting arm 2 provided at its upper end with a head 3 designed to fit into the socket

of a holder of a tape tensioning device, such as that shown in my pending application Ser. No. 128,062, filed February 27, 1937. At its lower end this arm is provided with a circular disk-like hub portion 4, and this part of the device is machined to receive and support an arbor 5, the latter being secured rigidly to the arm by a set screw 6.

The tape tensioning pulley or drum 7 is mounted to revolve on the arbor 5 and it preferably is made of a sheet metal construction. As shown, this drum is composed of two sheet metal sections *a* and *b* forming the opposite sides of the device and provided with peripheral flanges *c* and *d*, respectively, which telescope, one within the other, the outer flange being crimped over, as shown at *e*, to hold the two parts securely together at the periphery. At their inner margins these two sections are shaped around, and secured rigidly to, the outer race 8 of a ball bearing. Between this member and the enlarged portion adjacent to the periphery, the two sections are brought together face to face to provide a relatively thin annular connecting area, the sections being locked together in this region by a series of tongues *f*. This arrangement provides a light weight, relatively inexpensive drum structure well adapted to use in spinning and similar machines. It can, however, be replaced, if desired, with other forms of drums or pulleys.

The mounting shown for the drum 7 includes a series of balls 9 running in the groove of the race 8 and in a cooperating groove or raceway formed in the arbor 5. This construction thus serves to position the drum both radially and axially with reference to the arbor.

Lubricant is supplied to this bearing from a chamber or hole 10 drilled axially in the arbor and communicating with the bearing chamber by means of a hole 12. Preferably the chamber 10 is partly packed with felt or other fibrous material held in place by a thimble 13 pressed into the end of the hole in the arbor, this thimble having a central aperture through which the end of an oil can nozzle may be inserted to partially fill the chamber. Oil retaining washers 14—14 are pressed into the outer ends of the ball race 8 where they revolve with it and prevent any substantial escape of oil from the bearing. It will be observed that the oil hole 12 opens into the bearing chamber at a point between the washers. Obviously this provision for supplying oil to the bearing can be replaced by a grease cup mounted in the end of the arbor 5.

in place of the thimble 13, in which event the felt packing will not be used.

It is customary to provide a fork on each side of the pulley or drum for the purpose of catching the tape in the event that it runs off the pulley, due to misalignment or for any other reason. One fork is fastened to or made integral with the pulley supporting arm, while the other is formed at the end of a yoke running from the supporting arm around the pulley to the opposite side. This construction is objectionable both because it affords a place for fly to accumulate, and also for the reason that it adds materially to the weight which must be counter-balanced. It is one of the objects of this invention to avoid these difficulties and to eliminate the yoke. To this end the arm 2 is provided with an extension or tip 15, preferably integral with the arm, and inclined outwardly away from the drum 7, as best shown in Fig. 3. A corresponding member 16 is provided at the opposite side of the drum and preferably is made integral with a disk-like collar 17, similar to the part 4, and secured rigidly to the left-hand end of the arbor 5, Fig. 2, by means of a set screw 18. Thus the two elements 15 and 16 cooperate to form a tape catching fork, and the collars 4 and 17 cooperate with them, respectively, to provide angular pockets in which the tape lodges in the event that it slips off in one direction or another.

It will be evident from the foregoing that the invention provides a tape tensioning pulley of exceptionally simple construction, of light weight, and so organized that it can be manufactured very economically. The anti-friction mounting of the drum and the provision for lubrication of the bearing make the device economical of power and the nature of the organization is such that relatively little area is exposed for the accumulation of fly. In this connection it should be noted that the collars 4 and 17 substantially fill the annular cavities or spaces in the drum adjacent to its hub and act as shields or guards to protect the bearing from fly and dirt. It will be observed that the drum has annular shoulders closely encircling the peripheries of said collars or hub members 4 and 17. Preferably the collar 17 is provided with a depending lip 20 designed to catch any oil which may be carelessly left on the end of the arbor 5 during the oiling operation and guiding such excess to a tip projecting downwardly beyond the adjacent surfaces of the collar. This tip also is spaced axially outward far enough to cause any drip from it to fall clear of the drum, even though the drum may be tipped in a clockwise direction, Fig. 2, into an angle considerably off the vertical.

In manufacturing the device the drum usually is assembled on the arbor with its ball bearing, and this assembly subsequently is handled as a unit, the only additional assembling operation being to mount the arbor in the arm 2 and to secure the collar 17 on the arbor.

While I have herein shown and described a preferred embodiment of my invention, it will be understood that the invention is susceptible of embodiment in other forms without departing from the spirit or scope thereof.

Having thus described my invention, what I desire to claim as new is:

1. A tape tensioning pulley structure for spinning frames and the like, comprising a supporting arm, an arbor supported at one end by said arm, a drum mounted on said arbor for rotation, a collar secured on said arbor at the end thereof opposite said arm, and members at opposite sides of said drum rigid with said arm and said collar, respectively, for catching the tape if it runs off said drum, each of said members having its free end located on the same side of the drum as the collar and arm with which it is rigid. 25

2. A tape tensioning pulley structure for spinning frames and the like, comprising a supporting arm, an arbor supported at one end by said arm, a drum mounted on said arbor for rotation, a collar secured on said arbor at the end thereof opposite said arm, said arm and said collar being provided with integral extensions for catching the tape if it runs off the drum, each of said extensions having its free end located on the same side of the drum as the collar and arm with which it is integral. 30

3. A tape tensioning pulley structure for spinning frames and the like, comprising a supporting arm, an arbor supported at one end by said arm, a drum, ball bearings supporting said drum on said arbor and positioning the drum both radially and axially in the structure, and a collar secured on said arbor at the end thereof opposite said arm, said arm and collar being provided with integral extensions for catching the tape if it runs off the drum, each of said extensions having its free end located on the same side of the drum as the collar and arm with which it is integral, said collar and said arm having parts at opposite sides of said bearings extending radially beyond the bearing and co-operating with adjacent surfaces of the drum to substantially enclose said bearings and the hub portion of the drum. 50 55
